CHORD ORGAN

William Macowski, Jr., Montclair, N.J., assignor to
Magnus Organ Corporation, Linden, N.J.

Filed Mar. 13, 1970, Ser. No. 21,892

Term of patent 14 years

Int. Cl. D17—01

U.S. Cl. D56—2

FIG. 1 illustrates a front view of a chord organ according to the invention;

FIG. 2 illustrates a top view of the chord organ of FIG. 1;

FIG. 3 illustrates a right side view of the chord organ of FIG. 1; and

FIG. 4 illustrates a rear view of the chord organ of FIG. 1.

I claim:

The ornamental design for a chord organ, as shown.
